Arthur C. Greenlee

UNITED STATES PATENT OFFICE.

ARTHUR C. GREENLEE, OF FERGUS FALLS, MINNESOTA.

DENTAL PLUGGER.

SPECIFICATION forming part of Letters Patent No. 363,630, dated May 24, 1887.

Application filed December 6, 1886. Serial No. 220,859. (No model.)

To all whom it may concern:

Be it known that I, ARTHUR C. GREENLEE, a citizen of the United States, residing at Fergus Falls, in the county of Otter Tail and State of Minnesota, have invented a new and useful Attachment for the Dental Engine—viz., a Right-Angled Plugger—of which the following is a specification.

My invention relates to an improvement in the attachments of the dental engine which are commonly used for inserting the filling of teeth; and the objects of my invention are, first, to provide an attachment for the dental engine which shall fill a tooth by means of blows delivered at right angles to the driving-shaft; second, to provide an attachment for the dental engine which shall operate at any re-entrant angle between ninety degrees and sixty degrees inclination to the driving-shaft; third, in such a right-angled dental plugger to provide a means for holding the plugging-shaft at any required inclination to the operating-shaft; fourth, to provide in such a right-angled plugger a combination of mechanism which shall convert the rotary motion of the shaft driven by the dental engine into a reciprocating motion of the shaft which carries the plugging-tool; fifth, in such a right-angled dental plugger to provide a means for regulating the length of the stroke of the reciprocating bar or shaft which carries the plugging-tool; sixth, in such a right-angled dental plugger to provide a means for regulating the force of the blows which are to be given by said plugger; seventh, in such a right-angled dental plugger to provide a means for keeping the follower attached to the plugging-shaft in constant contact with the cam which operates the same. I attain these objects by means of the mechanism illustrated in the accompanying drawings, in which—

Figure 1 is a vertical section of the entire machine, and Fig. 2 a view of the working-cam B.

The handle T, to which are riveted or fastened in any substantial manner the hanger N and the cylindrical tube K, oscillating upon journals M, which are supported upon opposite sides of said cylindrical tube in holes in the hanger N, constitutes the frame-work of the machine.

The cylinder K, which contains the plugging-shaft, is held at right angles to the operating-shaft A by means of the brace O, which is attached, by a ball-and-socket joint, S, at the 55 end next the plunger-cylinder, to the adjusting-nut G, whose use will be hereinafter explained, and at the other end carries the pin P, which slides in the spiral groove Q of the collar R, the lower end of said brace O sliding 60 longitudinally in a slot cut in the hanger N.

In the handle T the operating-shaft A revolves, which is connected to the dental engine, and has the cam B attached to it. Against the periphery of this cam B the arm or follower C, rigidly attached to the plugging-shaft D, is held in contact by the spiral spring E, the action of such combination being that as the cam B is revolved the follower C is brought to the point U and the spring E is compressed. 70 A further revolution of the cam B releases the follower C from contact therewith, and the pressure on the spring E being removed, the plugging-shaft D, with its tool J and arm or follower C, is projected through the distance U 75 V, when the follower C again comes in contact with the cam B. The cylinder K is moved to a position at any desired angle between a right-angle and one of sixty degrees inclination to the operating-shaft by turning the collar R, which 80 causes the pin P, and with it the brace O, to be raised or lowered. The collar R is constructed to fit very closely around the hanger N, so that it will remain in any required position, thus holding the brace O, and with it the cylinder 85 K, in the position desired by the operator until the collar R is again rotated.

The dotted figure of the plunger-cylinder, as shown by S' D' in Fig. 1, illustrates the position of the said cylinder when inclined at an 90 angle of sixty degrees to the operating-shaft.

The length of stroke U V may be shortened or subdivided by turning the adjusting-nut I in such a way as to move the buffer-block H to the left, as shown in Fig. 1, so that, instead 95 of being stopped at V by the cam B, the plunger-shaft may be stopped by the collar W striking against the buffer-block H.

To decrease the force of the blow of the plunger, the compression-block F may be moved 100 toward the left, as shown in Fig. 1, by turning the adjusting-nut G, thus decreasing the

pressure upon the spring E and the force of the blow delivered by the plunger; or it may be moved to the right by turning the nut G in the opposite direction, thus compressing the spring E, with which the shaft D is propelled upon releasing the follower C from contact with the cam B.

As the cylinder K is moved into position shown by the dotted lines, the follower C will be thrown out of contact with the cam B, and to bring them again in contact the compression-block F is pushed down toward the right by turning the adjusting-nut G until the follower C strikes the cam B at V and the required tension upon the spring E is obtained. At the same time the buffer-block H is drawn down toward the right until the collar W just comes in contact therewith.

Having thus described my invention, what I claim as new, and desire to secure by Letters Patent, is—

1. In a right-angled dental plunger, the combination of the handle T, hanger N, journals M, plunger-cylinder K, slotted at L, operating-shaft A, rotating cam B, follower C, plunger-shaft D, spring E, tension-block F, adjusting-block G, ball-and-socket joint S, and arm O, longitudinally placed in a slot in the hanger N and bearing a pin, P, all substantially as described.

2. In a dental plunger, the combination of

the collar R, closely encircling hanger N and arm O, and having a spiral slot, Q, cut therein, the pin P, attached to the arm O, constructed to travel in slot Q, joint S, and the journals M, supporting cylinder K in the hanger N, whereby the angle of the plunger to the operating-shaft may be varied, substantially as described.

3. In a dental plunger, the combination of a shaft, A, the cam B, follower C, attached to plunger-shaft D, spiral spring E, and compression-block F, substantially as shown, and for the purpose specified.

4. In a dental plunger, the combination of a cylinder, K, a buffer-block, H, constructed to slide in a slot, L, in the upper portion of the hanger N, and the adjusting-nut I, revolving in the cylinder K, substantially as described.

5. In a dental plunger, the combination of the cylinder K, a compression-block, F, sliding in a slot, L, in the upper portion of the hanger N, and the adjusting-nut G, rotating in the cylinder K, substantially as described.

6. In a dental plunger, the combination of a cylinder, K, compression-block F, adjusting-nut G, buffer-block H, and adjusting-nut I, substantially as and for the purposes specified.

ARTHUR C. GREENLEE.
